UNITED STATES PATENT OFFICE.

GEORGE ALBERT PATTERSON, OF BANGOR, MAINE.

TRANSFER APPARATUS.

1,102,072.

Specification of Letters Patent. Patented June 30, 1914.

Application filed June 10, 1910. Serial No. 566,241.

To all whom it may concern:

Be it known that I, GEORGE ALBERT PATTERSON, a citizen of the United States, residing at Bangor, in the county of Penobscot 5 and State of Maine, have invented certain new and useful Improvements in Transfer Apparatus; and I do hereby declare the following to be a full, clear, and exact description of the invention, such as will enable others skilled in the art to which it appertains to make and use the same.

This invention relates to improvements in transfer apparatus primarily for use in conjunction with paper making machinery.

15 The main and primary object of the present invention is the provision of a transfer device designed to be interposed between the platers and the making-up tables and serving to convey the forms, which are employed for imparting linen finish to paper, from the tables upon which such forms are made up to the platers. The present invention, therefore, dispenses with the manual handling of the heavy forms, and accomplishes a material saving in time and labor.

25 The invention also aims to provide a transfer device capable of working about a fixed or pivotal point, being movable in the arc of a circle, and thereby being adapted to serve a plurality of making-up tables with equal facility to transfer the forms from each of the tables as occasion for such transfer may arise.

35 Furthermore, the invention also aims to provide transfer apparatus the parts of which are so organized as to render the apparatus extensible, whereby to reach those making-up tables which are more or less remote from the plater, and permit the forms from such tables to be transferred to the plater with ease and convenience.

45 With these general objects in view, and others which will appear as the nature of the improvements is better understood, the invention consists substantially in the novel construction, combination and arrangement of parts hereinafter fully described, illustrated in the accompanying drawings, and 50 pointed out in the appended claims.

55 In the drawings Figure 1 is a diagrammatic view illustrating the relation of the herein described transfer apparatus to a plater and the making-up tables usually associated therewith. Fig. 2 is a side ele-

vation of the transfer apparatus. Fig. 3 is a top plan view thereof. Fig. 4 is an end elevation, viewing the apparatus at the end upon which the forms are fed from the making-up tables. Fig. 5 is a similar elevation, the point of view being at the discharge end of the apparatus, a portion being in section.

Referring in detail to the accompanying drawings, and more particularly to Fig. 1 thereof, the numeral 1 designates a plater for paper finishing. As is well known in the art, the forms for imparting the finish to the paper are made up prior to the introduction of the same to the plater, and for this purpose suitable tables are employed. These making-up tables are designated by the numeral 2, and are located in juxtaposition to the plater 1 so that when the forms are complete they may be transferred to the plater. By reason of the weight of the forms, it is a laborious task to effect the transfer under the conditions which hitherto have prevailed in the art, and, as before premised, it is the object of the present invention to provide apparatus whereby to effect the transfer in question with a saving of labor and time. To this end, a transfer device 3 is arranged between the plater 1 and the making-up tables 2, the location 75 of the transfer device 3 being such that the same will serve all of the making-up tables 2, as occasion may require, for the transfer of the forms from each of the tables.

The particular construction of the transfer device 3 is set forth clearly in Figs. 2, 3, 4 and 5, and reference is made to these figures for a clear understanding of such construction. In the views in question, the numeral 4 designates the sides of the transfer device. These sides are formed of elongated straps or bars, and two of these bars are employed at each side, but spaced apart for a purpose to be presently stated. The sides 4 are mounted upon terminal bolsters 5, each of which is in the form of a plate, the plates 5 being located adjacent to the ends of the sides 4, and arranged between the bars of each side, and resting upon the bolster plates 5, are spacing blocks 6, the latter being in the form of U-shaped angle irons. These angle irons are suitably connected to the bolster plates 5, said plates connecting and supporting the sides 4. At the inner end of the transfer apparatus, or 110

that end which is immediately contiguous to the plater, is a pedestal 7. This pedestal comprises a tubular standard having a suitable base 8, the upper end of the standard having fitted therein a plug 9 the upper end of which is reduced to form a trunnion 10. Connected to the upper end of the standard, preferably by screw threading, is a supporting disk 11, and upon which disk 11 is mounted the bolster plate 5 which is located at the discharge end of the transfer device. This disk 11 forms a bearing head for the pedestal. The bolster plate 5 referred to has an opening 12 which receives the trunnion 10, a holding disk 13 being employed to retain the bolster plate 5 upon said trunnion, and through the medium of the latter it will be seen that the bolster plate 5 has a pivotal connection with the pedestal 7, so that the transfer device is capable of a swinging movement on the pedestal with the trunnion 10 as its center.

For supporting the feed end of the transfer device a depending leg 14 is employed. This leg comprises a plurality of struts 15 the upper end of each of which is provided with an inwardly-extending attaching flange 16, which flanges are suitably connected to the bolster plate 5 adjacent to the feed end 30 of the apparatus. These struts 15 are arranged in pairs, the members of each pair converging at their lower ends and being mounted upon the axle 17 of a bearing wheel 18. This wheel 18 supports the feed end of the apparatus in such manner as to permit the latter readily moving from table to table, and in order that the leg 14 may be braced and held substantially rigid with the other portions of the apparatus, an inclined brace bar 19 extends from the axis of the wheel 18 up to one of the sides 4. The ends of the bar 19 are flattened, the lower end being fitted upon the axle 17, while the upper end is connected, as at 20, to one of the sides 4 at a point substantially midway the ends of the side. At this point is also arranged a transversely-extending brace 21, the ends of which are connected to the sides 4, and brace the latter at the point indicated. To facilitate movement of the forms as they pass upon the transfer device, a plurality of bearing rolls 22 is employed. Each of these rolls is provided with outwardly-extending trunnions 23, and said trunnions 55 are received by notches 24, formed in the upper edges of the sides 4, and constituting bearings for said trunnions. The rolls 22, therefore, are seated between the bars constituting each side 4, but a portion of the periphery of said rolls extends above the upper edges of said bars, so that the forms will readily move over the rolls 22 as the forms are directed throughout the length of the sides. It is obvious that the rolls 22 60 may be readily removed from their bearings

when occasion demands, the notches 24 freely permitting this.

There are conditions when it is impossible to arrange the making-up tables 2 in the arc of a circle, or in such relation to the transfer apparatus that each of the tables will be removed therefrom the same distance as the others. Under these conditions some of the tables are more remote from the transfer apparatus than others, or some portions of certain of the tables will be more remote than other portions. These conditions are exemplified in Fig. 1 of the drawings. To permit transfer of the forms under these conditions the apparatus is provided with an extension frame 25 which is slidably mounted between the sides 4 at the feed end of the apparatus. The outer end of the extension frame 25 has a terminal bar 26 the ends of which project beyond the sides of the frame 25, and mounted upon said projecting ends are U-shaped bearings 27 in which are journaled bearing rolls 28. These rolls are similar to the rolls 22 and are also mounted in a similar manner. By referring to Fig. 3 it will be observed that the rolls 28 are also arranged in alinement with the rolls 22. Arranged transversely of the frame 25, and slightly removed from its outer end, is an elongated bearing roll 29 designed to sustain the weight of the forms, when the frame 25 is extended, as the forms pass from the rolls 28 and before they reach the outermost of the rolls 22. This roll 29 is supported in a manner similar to the rolls 22 and 28.

To prevent the extension frame 5, when the same is projected, from sagging or being forced by the weight of the forms below the plane of the apparatus, a plurality of inwardly extending bolts or pins 30 is arranged in the sides 4, preferably immediately above the bolster plate 5 which is adjacent the feed end, said bolts or pins extending above the sides of the frame 25, and a supporting bar 31 is also arranged transversely of the sides 4 at a point between the bolster plate just referred to and the extremity of the feed end of the apparatus. The frame 25 rests upon the bar 31, and the latter in conjunction with the bolts or pins 30 will always maintain the extension frame 25 in horizontal alinement with the body of the apparatus.

To limit the outward movement of the extension frame 25 the inner end thereof is provided with a depending stop pin 31'. This pin is projected sufficiently below the frame 25 to contact with the bolster plate 5 adjacent the feed end of the apparatus, so that it will be seen said stop pin precludes displacement of the extension frame from the body of the apparatus when the same is moved outwardly.

The use of the herein described transfer

apparatus is obvious, but briefly stated it is as follows: With the invention positioned as illustrated in Fig. 1, the discharge end thereof is in close proximity to the plater. 5 Forms having been prepared upon the making-up tables 2, the apparatus is swung to the table from which the transfer is to be effected, and if the table is too remote for the length of the apparatus to reach the 10 same, the extension frame 25 is projected outwardly until its outer end is sufficiently near the table to receive the form or forms therefrom. The form to be transferred is now moved upon the extension frame, and 15 from the latter onto the body of the apparatus, the bearing rolls 28, 29, and 22 affording a rolling contact with the forms, and by reason of such rolling contact it is obvious that but slight friction occurs in 20 the transit of the forms. As the latter pass along the body of the apparatus, they move from roll to roll, there being no direct contact between the forms and the sides, and after having traversed the length of the 25 device they are introduced to the plater 1. In positioning the device with respect to the several tables, the same swings about the pedestal 7, moving freely upon the bearing wheel 18, and this facilitates free movement 30 of the apparatus for positioning purposes.

While the present invention is primarily designed for use in connection with paper making machinery, it is obvious that it is not restricted to such use, but is capable of 35 use in other relations where a transfer device is desired.

Having thus described the invention, what is claimed as new, and desired to be secured by Letters Patent, is:

40 1. In an apparatus of the character described, a pedestal, a body associated with said pedestal and comprising a frame each side of which is formed of spaced members, means for connecting and supporting the 45 sides of said frame, one end of said frame being pivotally connected with said pedestal, whereby the body is capable of swinging on said pedestal, bearing rolls journaled in said sides, an extension frame associated with 50 said body and slidably mounted in relation thereto, outstanding bearing rolls carried by the outer end of said extension frame and arranged in alinement with the rolls of the body, and a bearing roll journaled in the extension frame between said outstanding 55 rolls.

2. In an apparatus of the character described, a pedestal having a bearing head, a body associated with said pedestal and 60 comprising a frame each side of which is formed of spaced members, terminal bolsters for said sides, one of said bolsters being pivotally connected with said pedestal and bearing upon the head thereof, whereby the body is 65 capable of swinging on said pedestal, bearing

bearing rolls journaled in said sides, and means for sustaining the sides in spaced relation.

3. In an apparatus of the character described, a pedestal having a bearing head, a body associated with said pedestal and comprising a frame each side of which is formed of spaced members, bolsters for said sides, one of said bolsters being pivotally connected with said pedestal and bearing upon the head thereof, whereby the body is capable of swinging on said pedestal, bearing rolls journaled in said sides, and spacing blocks arranged between the members of each side for sustaining said members in spaced relation. 75 80

4. In an apparatus of the character described, a pedestal having a bearing head, a body associated with said pedestal and comprising a frame each side of which is formed of spaced members, bolsters for said sides, one of said bolsters being pivotally connected with said pedestal and bearing upon the head thereof, whereby the body is capable of swinging on said pedestal, bearing rolls journaled in said sides, and a supporting leg connected to the other of said bolsters and depending therefrom. 85 90

5. In an apparatus of the character described, a pedestal having a bearing head, a body associated with said pedestal and comprising a frame each side of which is formed of spaced members, bolsters for said sides, one of said bolsters being pivotally connected with said pedestal and bearing upon the head thereof, whereby the body is capable of swinging on said pedestal, bearing rolls journaled in said sides, an extension frame associated with said body and mounted to move in relation thereto, and bearing rolls carried by said frame. 95 100 105

6. In an apparatus of the character described, a pedestal having a bearing head, a body associated with said pedestal and comprising a frame each side of which is formed of spaced members, bolsters for said sides, one of said bolsters being pivotally connected with said pedestal and bearing upon the head thereof, whereby the body is capable of swinging on said pedestal, bearing rolls journaled in said sides, an extension frame associated with said body and mounted to move in relation thereto, and means for limiting the movement of said extension frame on said body. 110 115 120

7. In an apparatus of the character described, a pedestal having a bearing head, a body associated with said pedestal and comprising a frame each side of which is formed of spaced members, bolsters for said sides, one of said bolsters being pivotally connected with said pedestal and bearing upon the head thereof, whereby the body is capable of swinging on said pedestal, bearing rolls journaled in said sides, an exten- 125 130

4

sion frame associated with said body and mounted to move in relation thereto, and bearing rolls arranged at the sides of said extension frame and in alinement with the bearing rolls carried by the body.

8. In an apparatus of the character described, a pedestal comprising a tubular standard, a plug arranged in said standard and provided with a trunnion, a supporting member associated with said standard, a

body pivotally connected to said trunnion and mounted for movement upon said supporting member, and means for retaining the body in engagement with said trunnion.

In testimony whereof I affix my signature, in the presence of two witnesses.

GEORGE ALBERT PATEESEN.
